CLAIM

The ornamental design for a container holder, as shown and described.

DESCRIPTION

FIG. 1 is a top, right, front perspective view of a container holder embodying our new design;

FIG. 2 is a right elevational view thereof, the left elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a section view along line 7-7 of FIG. 5.

The broken line representations of supports and internal structure in the views are for illustrative purposes only and form no part of the claimed design.
